[57] CLAIM

The ornamental design for a liquid storage tank gauge, as shown and described.

DESCRIPTION

FIG. 1 is a front, right side and top perspective view of a liquid storage tank gauge showing our new design;

FIG. 2 is a front elevational view thereof;

FIG. 3 is a left side elevational view thereof;

FIG. 4 is a right side elevational view thereof;

FIG. 5 is a rear elevational view thereof;

FIG. 6 is a bottom plan view thereof; and,

FIG. 7 is a top plan view thereof.

The broken line showings of indicia, a partial liquid storage tank, float and support are for environmental purposes only and form no part of the claimed design while portions have been omitted for ease of illustration in the drawing with the exception of FIG. 2.
